UNITED STATES PATENT OFFICE.

SAM B. LAWRENCE, OF ANDERSON, SOUTH CAROLINA, ASSIGNOR TO DRAPER CORPORATION, OF HOPEDALE, MASSACHUSETTS, A CORPORATION OF MAINE.

WARP STOP MOTION FOR LOOMS.

Application filed February 12, 1924. Serial No. 692,210.

To all whom it may concern:

Be it known that I, SAM B. LAWRENCE, a citizen of the United States, and resident of Anderson, in the county of Anderson and State of South Carolina, have invented an Improvement in Warp Stop Motions for Looms, of which the following description, in connection with the accompanying drawings, is a specification, like characters on the drawings representing like parts.

This invention relates to warp stop mechanisms for looms whereby the operation of the loom is arrested when a warp thread breaks or becomes too slack for weaving purposes.

As now ordinarily constructed, warp stop mechanisms are provided with a series of drop wires which are normally supported by a warp thread during weaving, and associated with the drop wires there is a drop wire guide for directing the movement of the drop wires. A feeler or vibrator is usually associated with the warp stop mechanism and has its movement arrested when one or more of the drop wires fail to be supported by the warp threads during weaving, and such arrest of the feeler or vibrator is utilized in stopping the loom.

During the weaving operation the drop wire guides are moved in their supports as the shedding mechanism changes the shed, the result being that the drop wire guides wear rapidly at their supported ends and have to be renewed frequently. Moreover, when the warp in a loom is to be changed it is easier to remove the drop wires while still connected with their warp threads, tie the lease in the warp threads and draw the new warp threads through the drop wires by tying them to the ends of the old warp threads and withdrawing the old threads. It is thus desirable to support the drop wire guides, which usually pass through slots in the drop wires, so that they may be readily removed from the loom, and consequently the end supports for the drop wire guides are usually formed with open bearings for the ends of the drop wire guides.

The present invention has for one of its objects the provision of means for holding the drop wire guides in their end bearings without movement and to readily relieve the ends of the drop wire guides when they are to be removed.

An important feature of the present in-

vention, therefore consists in end supports for the drop wire guides and a retainer which is movable into engagement with the ends of the drop wire guides to hold them immovable in their supports and is removable from its operative position to readily permit the removal of the drop wire guides.

The novel features of the invention and new combination of parts will best be made clear from the following description and the accompanying drawings of one good form of the invention.

In the drawings:

Fig. 1 is a perspective view of the main parts of a warp stop mechanism, only one end portion of said mechanism being shown, it being understood that the opposite end portion is, or may be, of substantially the same construction;

Fig. 2 is an enlarged perspective view showing the drop wire guide retainer withdrawn from its retaining position to permit the drop wire guide to be readily removed from its supports;

Fig. 3 is a cross-section of the warp stop mechanism and adjacent one end thereof; and

Fig. 4 is an enlarged cross-section on the line 4-4 of Fig. 3.

It has not been deemed necessary herein to show and describe the transmission mechanism for effecting loom stoppage when the feeler or vibrator is arrested by a drop wire, since such mechanism is now understood and the details thereof form no essential part of the present invention.

Adjustably mounted at each side of the loom frame 1 is a bracket 2 which may be secured in place by a bolt 3 passing through a slot 4 in the bracket, such bracket forming a convenient support for the main portions of the warp stop mechanism.

Each of the brackets 2, one at each side of the loom, has a down-turned portion 5 from which extend the supports 6 for the rock shaft 7. The rock shaft 7 is given a rocking or oscillating movement by suitable connections with a going part of the loom through the rod 8 connected at 9 to an arm 10 secured to the rock shaft. Supported on the rock shaft as by the arm 11, one of which is shown, is a feeler bar 12 which extends transversely of the loom frame, and is shown in the present instance as located below the drop wires.

- Extending upwardly from the bracket 2 is a slotted member 13, one at each side of the loom, into the slot of which extends an end of a warp support 14, in the present instance, and such warp support is held in its slotted member by a pin 15 extending through the slotted end of the warp support. The slotted member 13 is located above the down-turned portion 5 of the bracket 2 and may either be supported thereon or by the transverse member 16 which may itself be secured to the bracket by the lugs 17 and the usual securing bolts. The member 16 has the enlarged slotted end portions 18 into which extend the lease rods 19, one being shown at either side of the warp stop mechanism. The warp threads *a* extend from the warp beam towards the shedding mechanism and each alternate warp thread passes above and then below the lease rods 19, as usual, the crossing portion of the threads being preferably supported by the upper edge portion of the warp support 14.
- The drop wires 20 are arranged in one or more rows or banks and the drop wires of each row are supported by or hung upon the alternate warp threads *a*.
- Extending between the down-turned portions 5 of the brackets 2 are the transverse bars 21 towards and from which the feeler or vibrator 12 moves during its oscillating movements, the construction being such that should one of the drop wires fail to be supported by its warp thread, it will move into position between the lower edge of one of the bars 21 and the oscillating member or feeler 21 and arrest the movement of the latter, whereupon the loom will be stopped through any usual form of stop mechanism.
- The parts of the warp stop motion thus far described may be of any usual or desired construction, that shown and described herein being illustrative of one good practical form thereof.
- In the present instance of the invention, the drop wires 2 are shown as provided with the slots 22, the upper closed ends of which may properly be utilized for supporting the drop wires on their respective warp threads. While this form of drop wire is well adapted for a warp stop motion, and for support of the drop wires upon the warp threads, they may be otherwise formed, various constructions and forms of drop wires being already well-known.
- In the present instance, the drop wires 22 are guided in their movements by the drop wire guides 23 which, as shown, extend through the elongated slots 22 of the drop wires, and when the drop wires are properly supported by the warp threads the lower closed end portion of the elongated slots 22 may rest upon or be closely adjacent to the lower edge of each of the drop wire guides.

When the shed is changed, a portion of the warp thread is raised and another portion is lowered, with the result that the drop wire guides passing through the slots of the drop wires are alternately subjected to a lifting 70 and lowering movement.

The down-turned portion 5 of the bracket 2 as shown is provided on its inner face with an open bearing 24 into which the end of drop wire guides project when in operative position, and in the slots 24 is formed a stop 25 constituting a rest for the lower edge portion of the end of the drop wire guides. In the present instance, the stops 25 are constituted as pins.

Mounted upon each of the brackets 2 which in the present instance constitute the end supports for the drop wire guides is a drop wire guide retainer, shown in the present instance as the slide 26 which is confined to sliding movement to and from operative position with respect to the ends of the drop wire guides. In the present instance the slide 26 has projecting from its under surface a lug 27, shown as of general cylindrical form, which is slidable in a guideway or groove 28 formed in the bracket 2, the construction being such that while the retainer 26 may be moved towards and from engagement with the ends of the drop wire guides resting in their open bearings, it is constrained to movement towards and from operative position.

The drop wire guide retainer or slide 26 is preferably provided with a thumb piece 29, Fig. 2, whereby the slide or retainer may be withdrawn from or moved to operative position. In some instances it may be desirable to provide means for automatically moving the slide or retainer into operative 105 engagement with the ends of the drop wire guides, and in the present instance such means is shown as a spring 30 which may be conveniently housed in a recess 31 formed in the bracket 2 and bearing at one end 110 against the wall of the recess and at its other end against the projection 27 extending from the retainer, the construction being such that the retainer may be readily withdrawn from operative locking engagement 115 with the ends of the drop wire guides to permit their ready removal when desired, and upon release of the retainer it will automatically move to automatic locking engagement with the ends of the drop wire 120 guides.

Where the drop wire guide retainer is constituted as a slide, as shown, it is desirable that movement of the retainer to and from operative position be limited, and to this end, as shown, the slide 26 at each side thereof is provided with a slot 32 into which projects a stop or pin 33 extending upwardly from the bracket 2, the construction being such that when the slide or retainer is with- 130

drawn from its operative position, as indicated in Fig. 2, the drop wire guides 23 may be readily lifted from their open bearings in the end supports, and when moved to operative position over the ends of the drop wire guides they will be limited in the extent of such movement to locate them in operative position.

From the construction described as one good embodiment of the present invention, it will be apparent that when the drop wires 23 have their ends supported in the open bearings of the side supports or brackets, the slide or retainer 26 will retain them immovable in such bearings by engagement, as shown, with the top surface of the drop wire guides, so that all wear of the ends of the drop wire guides due to the movement of the warp threads during weaving is overcome, and when the retainer or slide 26 is withdrawn or moved from its engagement with the ends of the drop wire guides, they may be readily removed from their open bearings along with the drop wires.

In the warp stop motion shown, two banks of drop wires and two drop wire guides are illustrated, but it will be apparent that any number of banks of drop wires and any number of drop wire guides may be employed, and it is equally apparent that instead of supporting the drop wires upon the warp threads by the closed portion at the upper end of the elongated slots, they may be associated with the warp threads by any of the usual means now employed in supporting drop wires upon the warp threads. It will also be apparent that while the advantages of the present invention are manifested in the particular character of the warp stop mechanism employed, the invention may be utilized in any other forms of warp stop mechanism wherein the drop wires are guided in their movements by drop wire guides, the ends of which are supported in bearings at the sides of the loom frame.

What is claimed is:

1. In a warp stop mechanism for looms, the combination of a series of drop wires, a drop wire guide, a support at the side of the loom for the end of the drop wire guide, a recess formed in the support constituting a guideway, and a retainer having a part extending into the guideway for directing the movement of the retainer to and from engagement with the drop wire guide.

2. In a warp stop mechanism for looms, the combination of a series of drop wires normally supported by the warp threads during weaving, a drop wire guide for guiding the drop wires, a support at the side of the loom having a bearing for the end of the drop wire guide, a sliding drop wire retainer on said support and having a lug confining the retainer to sliding move-

ment on the support into and out of engagement with the end of the drop wire guide.

3. In a warp stop mechanism for looms, the combination of a series of drop wires, 70 a drop wire guide, a bracket having a guideway extending in a direction transversely of the loom, and a sliding retainer mounted for movement in said guideway to and from engagement with the drop wire guide. 75

4. In a warp stop mechanism for looms, the combination of a series of drop wires normally supported by the warp threads during weaving, a drop wire guide for guiding the drop wires, a support at the side of the loom having a bearing for the end of the drop wire guide, a sliding drop wire retainer on said support and having a lug confining the retainer to sliding movement 80 on the support into and out of engagement with the end of the drop wire guide, and a spring acting upon the lug to slide the retainer into operative position. 85

5. In a warp stop mechanism for looms, the combination of a series of drop wires, 90 a drop wire guide, a bracket having a groove extending in a direction transversely of the loom, and a sliding retainer mounted upon the bracket and having a lug engaging said groove to confine the retainer to sliding 95 movement to and from operative position.

6. In a warp stop mechanism for looms, the combination of a series of drop wires, a drop wire guide, a bracket having a groove extending in a direction transversely of the loom, a sliding retainer mounted upon the bracket and having a lug engaging said groove to confine the retainer to sliding movement to and from operative position, 100 and a spring contained within said groove 105 to slide the retainer into engagement with the end of the drop wire guide.

7. In a warp stop mechanism for looms, the combination of a series of drop wires, a drop wire guide, a bracket having a groove extending in a direction transversely of the loom, a sliding retainer mounted upon the bracket and having a lug engaging said groove to confine the retainer to sliding movement to and from operative position, 110 a spring contained within said groove to slide the retainer into engagement with the end of the drop wire guide, and a stop for limiting the sliding movement of the retainer. 115

8. In a warp stop mechanism for looms, the combination of a series of drop wires, a drop wire guide, a bracket having a guideway extending in a direction transversely of the loom, and a sliding retainer mounted for movement in said guideway to and from engagement with the drop wire guide and provided with a thumb piece for sliding the retainer to and from operative position. 125 130

9. In a warp stop mechanism for looms, the combination of a series of drop wires, a drop wire guide, a bracket having a guideway, and a drop wire guide retainer constituted as a plate mounted for sliding movement upon the bracket and engaging the guideway.
10. In a warp stop mechanism for looms, the combination of a series of drop wires, a drop wire guide, a bracket having a guideway, a drop wire guide retainer constituted as a plate mounted for sliding movement upon the bracket and engaging the guideway, and a pin limiting the sliding movement of the plate.

In testimony whereof, I have signed my name to this specification.

SAM B. LAWRENCE.
